Primary Examiner — Marie D. Fast Horse(74) *Attorney, Agent, or Firm* — Anova Law Group, PLLC(57) **CLAIM**

The ornamental design for a personal medical alert base station, as shown and described.

DESCRIPTION

FIG. 1 is a perspective view of a personal medical alert base station showing my new design;

FIG. 2 is a top view thereof;

FIG. 3 is a left view thereof;

FIG. 4 is a right view thereof;

FIG. 5 is a bottom view thereof;

FIG. 6 is a front view thereof; and,

FIG. 7 is a rear view thereof.

The broken lines in the drawings depict parts of the personal medical alert base station that form no part of the claimed design.

1 Claim, 7 Drawing Sheets(56)
